UNITED STATES PATENT OFFICE.

JOSEPH T. ROBIN, OF NEW YORK, N. Y.

DESIGN FOR A SHOW-CASE.

SPECIFICATION forming part of Design No. 35,675, dated February 4, 1902.

Application filed September 27, 1901. Serial No. 76,806. Term of patent 7 years.

To all whom it may concern:

Be it known that I, JOSEPH T. ROBIN, a citizen of the United States, residing in the borough of Manhattan, city, county, and State 5 of New York, have invented and produced a new and original Design for Show-Cases, of which the following is a specification.

My invention consists of the design illustrated in the accompanying drawing, which 10 is a perspective view of a show-case embodying my invention.

A' A² designate sections of the show-case arranged one rearward of the other at a higher elevation, so as to have a step-like appear-

ance. The lower section A' is supported by 15 legs a' at the front corners, and the upper section A² is supported at the rear by legs a².

What I claim as my invention is—

The design for a show-case substantially as shown and described. 20

In testimony whereof I have signed my name to this specification in the presence of two subscribing witnesses.

JOSEPH T. ROBIN.
